UNITED STATES PATENT OFFICE

HAROLD T. BODKIN, OF CHICAGO, ILLINOIS

COMBINED WORKBENCH, CABINET AND TOOL SUPPORT

Application filed September 29, 1930. Serial No. 485,136.

This invention relates to improvements in a combined work bench, cabinet enclosure and tool support and generally comprises a cabinet structure having foldable leaves upon which are adapted to be mounted relatively light motor-driven metal and wood-working machine tools.

It is a purpose of the invention to so construct the cabinet that when the machine tools are not in use, the leaves upon which they are supported may be folded to form closing side walls of the main cabinet structure with the tools enclosed within the cabinet and whereby, when the tools are brought into use, the supporting leaves may be swung upward into horizontal extended relation and by turning the leaves on a horizontal axis the tools are brought into proper operative position.

It is further a purpose of the present invention to provide a driving motor within the cabinet which drives a horizontal shaft, each leaf including a shaft mounted thereon on the opposite side of the leaf from the tools and joined to the shaft within the cabinet by a pivoted connection which permits the reversal of the leaf to bring the tools into proper operative position.

My invention also contemplates the manufacture of a cabinet and folding leaves with the driving shafts whereby the user may install a driving motor and add each tool as he desires.

Further objects and advantages will be more readily apparent from the detailed description taken in connection with the attached drawings in which—

Figure 1 is a perspective view of the cabinet in closed position with the tools enclosed within the cabinet;

Figure 2 is a perspective view of the cabinet with the leaves extended into operative position for using the tools;

Figure 3 is a vertical section through the cabinet illustrating one of the leaves in horizontal position and the other folding leaf in vertical closed position;

Figure 4 is a vertical section taken on the plane indicated by 4—4 in Figure 3;

Figure 5 is an enlarged detail section illustrating the locking members, and

Figure 6 is a plan view of the top surface of one of the leaves.

As shown in Figure 1, the main part of the cabinet comprises a table 10 forming a work bench supported by the corner posts 12. The front and back side walls 14 are unbroken and rigid in position but the other side walls 16 are movable. The walls or leaves 16, when in closed position, conceal the interior of the cabinet and each of the leaves 16 has a pair of crossed legs 18 which are secured by hinges 20 to supporting blocks 22 attached to the lower corners of the leaves. The legs are held in folded relation by releasable clips 24 secured adjacent the top of the cabinet. A rotatable shaft 26 is mounted on the outer face of each of the leaves 16 by means of the journal bearings 28. Within the cabinet there is mounted a rotatable shaft 30 supported by the journal bearing 32 secured to a block 34, attached to the bottom surface of the top member 10. A pair of intermediate rotatable shaft members 36 are also mounted in axial alignment with the shaft 30 supported by the bearing support members 38 and blocks 40. A pair of slotted coupling members 42 are provided secured to the ends of the shaft 30 by set screws 44 and adapted to receive at their other ends the ends of shafts 36 which have driving pins 46 receivable in the slots 48, whereby the shafts 36 are rotatable with the shaft 30 but are longitudinally slidable with respect thereto. The shafts 36 extend slightly outward from the cabinet and are attached to the shafts 26 mounted on the leaves by the pivoted connections 50, as will be apparent from Figures 1 and 3.

By this arrangement each of the leaves 16 may be turned from its initial vertical position to a horizontal position by rotating about the pivoted connection 50. When a leaf 16 has been brought to horizontal position with the shaft 26 on its upper side, the leaf may then be rotated about the axis of the shaft 26 which will then be in alignment with the shafts 36 and 30 which will bring the face of the leaf which was initially

inside the cabinet to the top, as shown by the left-hand leaf of Figure 3. The entire leaf 16 may then be inwardly moved towards the cabinet by sliding in a horizontal plane which is permitted by the slotted coupling 42 and, as will be later described, the inner end of the leaf 16 will be securely held in position. The legs 18 may then be placed in supporting position to hold the outer ends of the 10 leaves.

The purpose and practical use of the folding cabinet which has been described consists in the provision for a convenient mounting for light motor-driven metal and wood-15 working tools upon the foldable leaves whereby the tools, when the cabinet is closed, are concealed within the interior of the cabinet and are entirely out of the way but when the user desires to operate the tools, he may 20 quickly unfold the cabinet, as described, and bring the tools into operative position so that they all may be driven from the shaft 30 within the cabinet.

In order to drive the shaft 30 there is provided a motor support 52 within the cabinet secured to the side walls 14. Upon the support 52 an electric motor 54, of the proper size, may be conveniently mounted. The motor has a pulley 56 while shaft 30 has a 25 cooperating pulley 58, whereby a driving belt 60 will couple the motor to the shaft 30. Suitable pulleys 62 may also be mounted at desired positions along the shafts 26 for driving through belts the machine tools 30 mounted on the opposite sides of the leaves 16.

A special feature of the present invention consists in the fact that the user of the cabinet may buy and install each tool as he desires 40 and in order to make the installation of the tools in proper positions relatively convenient, each of the leaves 16 may be suitably formed as shown in Figure 6, with slots 64 to receive driving belts and stenciled spaces 45 66 which indicate that certain tools should be mounted in certain spaces. The spaces 66 are also provided with drilled openings 68 to enable the bolting of the tool supports to the leaves. Figure 6 illustrates one of the 50 leaves upon which may be mounted a lathe, a sander and a saw. Other tools, such as indicated in dotted lines in Figure 2, may be mounted on the other leaf.

The manner of securely holding the inner 55 end of each of the leaves is illustrated in Figures 3, 4 and 5. The inner end of each of the leaves has a U-shaped cut-out portion 70 fitting over the protruding end of the shaft 36. When the leaf 16 is moved inwardly into 60 locking position, it slides under a cross member 72 forming an apron and the leaves 16 rest upon, at their ends, a pair of blocks 74 carried by depending members 76 which serve as stop members to limit the inward 65 movement of the leaves and each of the blocks

74 have pivotally secured thereto a cam-shaped locking member 78 which may be turned from its initial dotted line position, in Figure 5, to the full line holding position in which position the upper end is forced into a slot 80 in the supporting leaf. It will be readily apparent that the leaf will then be held securely in position and will not be dislodged by the vibration in driving the tools. By releasing one of the set screws 44, the 75 driving shaft 30 may be disengaged from the shaft 36 on one side and only one leaf may then be used in operative position, as in Figure 3.

It will be apparent that many changes may 80 be made in various details of construction without departing from the spirit of my invention as defined in the appended claims.

I claim:

1. In a cabinet, a movable leaf initially 85 forming a closing vertical side wall of said cabinet, a shaft rotatably journaled to the exterior surface of said leaf and a shaft rotatably journaled within said cabinet, pivotally connected to the shaft carried by said leaf whereby said leaf may be raised to horizontal position and rotated about the axis of the shaft to bring its initially inner surface to the top.

2. In a combined work bench and extension support for small machine tools, a cabinet having a flat upper surface forming a work bench, a movable leaf initially forming a closing side wall of the cabinet having machine tools mounted on its initially inner side 100 whereby said tools are concealed within said cabinet, a single pivotal and rotatable connection between the upper end of said movable leaf and said cabinet whereby said leaf may be raised to horizontal position and rotated to bring its initially inner side to the top.

3. In a support for machine tools, a stationary supporting member, a driving motor carried thereby, a drive shaft rotatably journaled to said supporting member adapted to be driven by the motor, a movable leaf member, a shaft rotatably journaled on one side of said leaf member, machine tools mounted on the other side of said member adapted to be driven from the shaft carried by said leaf and a pivotal connection between said drive shaft and said leaf member whereby said leaf member initially hangs in vertical position and whereby said leaf member may be raised to horizontal position and turned, through rotation of said shaft, to bring said machine tools to the top side of said leaf member.

4. In a cabinet structure, a relatively movable side wall; a longitudinally shiftable rotatable member carried by said cabinet; a pivotal connection between said movable side wall and said rotatable member whereby said side wall may be raised by turning about its 125

5 pivot to horizontal position and turned to bring its initially inner side to the top through rotation of said rotatable member then shifted longitudinally towards said cabinet to bring its inner edge beneath a stationary portion of said cabinet.

10 5. In a folding cabinet structure, a main cabinet having a top and foldable closing side walls, a pair of cooperating elements pivotally connected and respectively secured to said main cabinet and to a foldable side wall of said cabinet, said elements being rotatable as a unit relative to either said main cabinet or said foldable side wall whereby said movable side wall may be raised to horizontal position and rotated to bring its initially inner side to the top and means for supporting the outer end of said movable side wall when in raised position.

15 20 6. In a device of the character described, a main support, a member arranged to initially hang in vertical position and adapted to be raised to horizontal position and turned to bring its initially inner side to the top and a single pivotal and rotatable connection between said member and said main support.

25 7. In a device of the character described, a cabinet, a movable leaf member initially forming a closing side wall of said cabinet, means secured to the cabinet adapted to receive and hold the inner edge of said movable leaf after it has been raised to horizontal position and shifted longitudinally towards said cabinet and a pivotal rotatable and longitudinally shiftable connection between the upper end of said movable leaf and said cabinet.

30 40 8. In a combined work bench and extension support for small machine tools, a cabinet having a flat upper surface forming the work bench, a movable leaf initially forming a closing side wall of the cabinet, said leaf having machine tools mounted on its initially inner side whereby said tools are concealed within said cabinet, a drive shaft for the machine tools journalled to the opposite side of said leaf from said tools and means pivotally and rotatably connecting one end of said leaf to said cabinet whereby said leaf may be brought to horizontal extended position with respect to said cabinet with the tools on its upper side.

35 45 9. In a combined work bench and extension support for small machine tools, a cabinet having a flat upper surface forming the work bench, a driving motor supported within said cabinet, a movable leaf member initially forming a closing side wall of the cabinet, said leaf having machine tools mounted on its initially inner side whereby said tools are concealed within said cabinet, a drive shaft journalled to the outer side of said leaf member adapted to be driven by the motor when in operative position and means pivotally and rotatably connecting one end

of said movable leaf to said cabinet whereby said leaf may be brought to horizontal extended position with respect to said cabinet with the machine tools on the top side of said leaf.

70 10. In combination with a cabinet type work bench, a driving motor therein, a movable side wall of said cabinet adapted to have small machine tools mounted on its initially inner side, a driving shaft for said tools journalled to said side wall, means for supporting said movable side wall in extended horizontal operative position with the machine tools on the upper side of said movable side wall and with its end adjacent the cabinet rigidly braced within said cabinet and means for driving said shaft from said motor when said side wall is in operative position.

75 11. In a combined work bench and extension support for small machine tools, a cabinet having a flat upper surface forming a work bench, a movable leaf initially forming a closing side wall of the cabinet, said leaf having machine tools mounted on its initially inner side whereby said tools are concealed within said cabinet, a single pivotal and rotatable connection between said leaf and said cabinet whereby said leaf may be raised through pivotal movement to extended horizontal position and rotated to bring its initially inner side to the top and means for rigidly supporting said leaf when in extended horizontal position.

80 12. In a combined work bench and extension support for small tools, a cabinet having a flat upper surface forming a work bench, a driving motor supported within said cabinet, a movable leaf member initially forming a closing side wall of said cabinet, said leaf having machine tools fixed to its initially inner side whereby said tools are concealed within said cabinet, means connecting said leaf to said cabinet for movement to extended horizontal position with its initially inner side at the top, means for rigidly supporting said leaf in horizontal position and means for driving said tools from the motor within said cabinet.

85 13. In a combined work bench and extension support for small machine tools, a cabinet having a flat upper surface forming a work bench, a driving motor supported within said cabinet, a movable leaf member initially forming a closing side wall of said cabinet, said leaf member having machine tools fixed to its initially inner side, a rotatable drive gear journalled on one side of said leaf member, means connecting said leaf member to said cabinet for movement to extended horizontal position parallel to the flat upper surface of said cabinet, said leaf member when in extended horizontal position having its initially inner side on top whereby said machine tools are in operative position, means rigidly supporting said leaf
